UNITED STATES PATENT OFFICE.

FERDINAND KOCH, OF HANOVER, PRUSSIA, GERMANY.

WEIGHING-SCALES.

SPECIFICATION forming part of Letters Patent No. 404,290, dated May 28, 1889.

Application filed July 6, 1887. Serial No. 243,489. (No model.) Patented in Germany February 4, 1887, No. 40,124, and July 10, 1887, No. 42,373; in Belgium May 31, 1887, No. 77,514; in France June 22, 1887, No. 184,379, and in England June 23, 1887, No. 8,958.

To all whom it may concern:

Be it known that I, FERDINAND KOCH, manufacturer, a subject of the King of Prussia, and a resident of the city of Hanover, Province of Hanover, Kingdom of Prussia, German Empire, have invented certain new and useful Improvements in Scales, (for which I have obtained patents in the following countries: Germany, No. 40,124, February 4, 1887, Additional Patent No. 42,373, July 10, 1887; England, No. 8,958, June 23, 1887; France, No. 184,379, June 22, 1887; Belgium, No. 77,514, May 31, 1887,) of which the following is a complete specification in such full, clear, and concise terms that anybody who is skilled in the art to which the invention appertains or to which it is most nearly related can understand and use the same, reference being had therein to the accompanying drawings, in which similar letters designate similar parts in all the figures.

My invention relates to the class of scales known under the name of "Danish" or "Swedish" scales, which have a scale-pan on the end of a graduated beam, on which a weight slides, the method used till now for graduating the beam being by experiments and therefore very tedious and costly.

The object of my invention is to avoid these deficiencies by constructing the weighing-beam in two parts in such a manner that they can be adjusted in reference to each other by screws or other means.

I am aware that screws for adjusting the knife-edges of scales in reference to each other are not new; but it has never been attempted to adjust the part bearing or forming the sliding weight in reference to those parts which bear the common sets of knife-edges.

With reference to the accompanying drawings, Figure 1 is a side view of my improved scale or balance. Fig. 2 is a plan of the same. Figs. 3 and 4 show side views of modifications of the adjusting device. The knife-edge *d* can be adjusted on the pins *x* by means of the two set-screws *p* and *q*. Fig. 5 shows a side view of another modification of my improved scale-beam. Fig. 6 shows a top view of the

a, Fig. 1, is the support of the scale or balance. The weighing-beam consists of the two parts *g* and *h*. The graduated part *h* fits into the socket *g* and is pivoted on the pins *x*, while the short left-hand end rests between the screws *p* and *q*, by which it can be adjusted. The part or socket *g* bears the common two sets of knife-edges *d* and *c* and the arm *z*. On the knife-edge *d* hangs the scale-pan *e*, for weighing purposes. The object of my forming the beam so is on account of the center of gravity of the weight *l* not being in the same straight line with the knife-edges *c* and *d*, or that the line passing through the center of gravity of the weight *l* and the knife-edge *c* does not make the same angle with the horizon as a line passing through the knife-edges *c* and *d*, and unless this is the case the proper graduations can only be formed by experiment, and are different in length.

In my improved scales I can divide the graduated beam evenly, and without experimenting, after the different parts are put together, as all that is necessary is to adjust the screws *p* and *q* till the scale is in equilibrium.

The weight *l* is provided with a pawl, *k*, which catches in notches in the part *h* and is held fast by the spring *f*. *i i* are levers to facilitate the moving of the weight *l*, *o* being the point at which the graduations on the lever *h* are read off. *z* is an index-finger fastened to the part *g*, by which fractional weights can be read off in divisions marked on the graduated plates *s*. *e* is the scale-pan, in which the articles to be weighed are placed.

In the modification, Figs. 5 and 6, *h* is the graduated beam, to which the weight *l* is fixed. This arm or beam slides in the sleeve *m* and rests on the two knife-edges *d* and *d'*. *d'* is fixed to the sleeve *m*. *d* is fixed to the socket *g*. The sleeve *m* is hinged on the pins *x* to the socket *g*, which bears the set-screw *p*, by which the position of the knife-edge *d* can be altered to that of *d'*, and so allowing of an easy adjustment of the beam *h* in reference to *g*. *xx* are the supporting-pins, upon which the lever *h* turns, and *c* the supporting knife-edge of the socket *g* and beam *h* on the stand of the balance.

Having now fully described my invention, to

what I claim, and desire to secure by Letters Patent of the United States, is—

1. In scales or balances, the set-screws *p* *q*, the lever *h*, and socket *g*, the said lever being pivoted in the socket *g*, and the said socket *g* bearing the knife-edges *d* and *c* and being so arranged that the lever *h*, bearing or forming the sliding weight, is adjusted by means of said set-screws, so that the line passing through the center of gravity in the direction of its length can be adjusted with reference to the two knife-edges *d* and *c*, for the purpose as described.

2. In scales or balances, the lever *h* and socket *g*, the socket *g* being provided with the knife-edges *d* and *c*, and means for adjusting the position of said knife-edges in relation to the lever or beam *h*, which bears or forms the sliding weight, for the purpose as described.

In witness whereof I hereunto set my hand in presence of two witnesses.

FERDINAND KOCH.
